DESIGN FOR A BEVERAGE DISPENSING BOWL

Frank E. Wolcott, West Hartford, Conn., assignor to The Silex Company, a corporation of Connecticut

Application October 9, 1934, Serial No. 53,531

Term of patent 14 years

To all whom it may concern:

Be it known that I, FRANK E. WOLCOTT, a citizen of the United States, residing at West Hartford, in the county of Hartford and State of Connecticut, have invented a certain new, original, and ornamental Design for a Beverage Dispensing Bowl, of which the following is a specification, reference being had to the accompanying drawing, forming part thereof.

In the drawing,—

I claim:—

The ornamental design for a beverage dispensing bowl, substantially as shown.

In testimony whereof I affix my signature.

FRANK E. WOLCOTT.
